CLAIM

The ornamental design for an air fryer drawer, as shown and described.

DESCRIPTION

FIG. 1 is a perspective view of an air fryer drawer showing the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines are for environmental purposes only and do not form any part of the claimed design. The dot dash lines depict the boundaries of the claimed design and form no part thereof.

1 Claim, 6 Drawing Sheets
